EX

N° 948.

Design of Bracket.
By Sarah Moore Jr.

Patented Octo. 13. 1857.

Des. 948

Sarah Chase Jr. of Boston Mass:
Letters Patent No 948. Dated Oct 13th 1857

~~~~~
The schedule referred to in these Letters Patent & making part of the same.

~~~~~
To all whom it may concern:

Be it known that A. Sarah Chase Jr. of the City of Boston, in the County of Suffolk and State of Massachusetts, have invented or produced a new and original Design for a Shelf Brackett and I do hereby declare that the following is a full and exact description of the same.

2

Des. 948

Fig. 1. represents the design in detail with open panneled border at the side and top, together with the Griffin head, & scroll work.

What I claim as my invention, or production is, the open relief panneled border at the side, and top of the brackett- and the peculiar configuration of the Griffin head, in connection with the scroll work as shown in the drawing.
